UNITED STATES PATENT OFFICE

2,320,078

INTERCHANGEABLE COVERING MEMBER

Carnig A. Harpootlian, Brooklyn, N. Y., assignor
to Modern Accessories Inc., New York, N. Y., a
corporation of New York

Application April 7, 1941, Serial No. 387,302

1 Claim. (Cl. 41—5.5)

This invention relates to roll-stipplers having replaceable frictionally supported tubes or covering members made of material such as carpet, rubber, and the like, and used in impressing designs on coated surfaces, particularly on building walls being painted.

An object of this invention is to provide in combination with a rotatably mounted roll carrier or supporting member made of metal, a tube or covering member removably secured on said carrier, the said tube being easily removed when covered with paint and a clean tube mounted on the carrier.

Another object of this invention is to provide a tubular covering member made of carpet having cord-like nap, each of which is of substantially circular cross-section and being thereby adapted to stipple freshly painted surfaces.

Another object of this invention is to make the cord-like nap elements cylindrical, stubby, and spaced-apart from each other, so as to produce a design effect by large dots instead of lines and so that freshly painted surfaces will be stippled without absorbing or spattering the paint.

Another object of this invention is to make the covering member of a sheet of carpet which is rolled up into tubular form and has its meeting edges secured together by wire staples, each of the connecting staples passing through both of the meeting edges and being positioned below the nap of the carpet.

This application is an improvement on my application for Interchangeable Stippling Roller, Serial No. 354,624, filed August 28, 1940, Patent No. 2,234,761.

In the said patent application I have disclosed a covering member made of carpet cemented to a cardboard tube. I impregnated the cardboard tubes with a chemical such as glycerine or other repellent of paint-removing liquids, such as benzine or turpentine, to prevent softening and destruction of the tubes, when the said paint covered member is put into benzine or turpentine after stippling.

I have found in practice that repeated immersion of the paper tube softens and destroys its usefulness. Better results are obtained when the carpet has its meeting edges joined together by wire staples, each of which passes through both of the meeting edges, the carpet being rolled into tubular form so as to spread apart the nap and provide a clear base surface free of the nap before the staples are applied and

clinched on the under side of the base portion of the carpet.

Furthermore, I have found that by impregnating the base portion of the carpet with a layer of rubber cement without penetrating the nap, that the base portion is made non-absorbent and the internal diameter of the covering member is maintained constant after repeated immersion in paint removing solutions.

With the above and other objects in view, the invention will be hereinafter more particularly described, and the combination and arrangement of parts will be shown in the accompanying drawing and pointed out in the claim which forms part of this specification.

Reference will now be had to the drawing, wherein like numerals of reference designate corresponding parts throughout the several views, in which:

20 Figure 1 is a side elevation of an assembled stippling roller carrier, partly broken away to show the interior.

Figure 2 is a plan view of the tubular stippling covering member, partly broken away to show the interior, the view being on an enlarged scale.

Figure 3 is a cross-sectional view, the section being taken as on line 3—3 in Figure 2, on an enlarged scale.

30 In the illustrated embodiment of the invention, the numeral 10 indicates a tubular roller carrier comprising a metal casing 11 having end members 12, 12, fixedly secured at opposite ends of the casing.

Each end member 12 has a central aperture 13 designed to receive reduced bearing portions of an axle 14 on which the tubular carrier 11 is mounted for free rotation. Each end member 12 may have a flange 15 which causes the end members to remain in mechanically interlocked relation with the tubular casing and so that the axle is at all times freely rotatably mounted in relation to the assembled casing.

As shown in Figure 1, each end member 12 is positioned within the casing in a manner to provide a large central opening 16 serving to house threaded ends 17, 17, of the axle 14. Each end 17 terminates inwardly of one of the end faces of the casing 11. One threaded end 17 of the axle 14 has a wing nut 18 threaded thereon.

As shown in Figures 2 and 3, I have provided a tubular stippling covering member 20 comprising a sheet of yieldable material 22. The sheet material 22 preferably is a carpet having

cord-like nap 23, each of which is of substantially cylindrical cross section and adapted to stipple freshly painted surfaces without absorbing the paint or spattering it.

As shown in Figures 2 and 3, the meeting edges 24, 24' of the carpet 22 are connected by wire staples 25. The staples are positioned crosswise of the meeting edges and preferably in perpendicular relation thereto. The staples are applied to the carpet when the carpet is in rolled up tubular form. The nap at the meeting edges is spread apart to provide a substantially flat cleared off junction at the meeting edges. The staples are applied so as to pass through both meeting edges and the free edge portions of the staples are clinched against the inner surface of the carpet. The staples 25 are in spaced-apart relation along the length of the seam 26 and are positioned below the nap.

It has been customary heretofore to make stippling paint rollers integral with the roller carrier. In practice, it is found necessary to have an assortment of stippling rollers of various lengths, which is a detriment when the painter has to move a large number of tools from one location to another. With the removable and interchangeable structure herein described, the covering member may be readily removed from the roller carrier for cleaning the paint from the covering member and a clean covering member instantly applied. It is to be noted that I intend to use a number of sets of roller carriers and covering members, each set being of a different length, and all sets being used with the same handle 27. The cleaning operation of a covering member after use in stippling a painted surface is accomplished by placing the covering member in turpentine or in benzine or into another chemical which can dissolve and remove paint.

The covering member 20 is frictionally and removably mounted on the roller carrier 10. It is necessary to maintain the internal diameter of the covering member constant after repeated immersion in the paint removing solution. For this purpose I apply a coat of rubber cement 28 to the inner surface of the carpet. The layer of rubber cement imparts a degree of rigidity to the base layer 29 of the carpet 22 and maintains the tubular shape of the covering member.

The rubber coated inner surface prevents paint from seeping through the carpet. The rubber also provides a gripping surface causing the carpet to stick or adhere to the outer surface of the roller carrier. The rubber coating makes the base portion of the carpet substantially non-absorbent whereby its internal diameter is maintained constant after repeated immersion in paint removing solutions.

Figure 1 shows the assembled roller carrier 10 supported on a multi-membered shank integral with the handle 27. It will be noted that the upper portion 30 of the shank has a bent side 31, the uppermost end of which is horizontal and

has a threaded aperture 32. The aperture 32 is adapted for threaded engagement with one of the threaded ends 17 of the axle 14.

The lower portion 33 of the shank is positioned in right angular relation with the roller carrier and has a threadably separable portion 34. The shank portion 33 has a threaded extension 35 designed to enter a threaded aperture in the shank portion 30. The shank members 30 and 33 may be of such length as to reach the ceiling portion of the room being painted and this makes the threaded portion 34 subject to breakage. To prevent such breakage I provide a tubular outer member 36 fixed to shank member 33 and having a slight clearance hole in its upper portion to receive the shank member 30 in supported relation. Breakage of the shank members is thus entirely prevented.

In assembling a roller carrier and handle, the user aligns the threaded aperture 32 of the shank member 31 with one of the threaded ends 17 of the axle 14 and engages the wing nut 18 and rotates the axle and thereby brings the said members into operative engagement.

It is to be noted that instead of connecting the meeting edges 24, 24' by wire staples, I may connect the said meeting edges by sewing them together. I may also connect the meeting edges by cementing a tape thereto at the interior surface of the carpet and lengthwise of the junction.

The junction of the axle 14 and the bent side 31 of the handle portion 30 is reinforced by a tubular outer member 37 which is integral with the axle at one end and embraces the handle portion 31.

In accordance with the patent statutes I have described and illustrated the preferred embodiment of my invention, but it will be understood that various changes and modifications can be made therein without departing from the spirit of the invention as defined by the appended claim.

I claim:

In a frictionally supported tubular covering member for a stippling roller of the class described, said covering member being made of carpet fabric having cord-like nap, said fabric having meeting edges connected together by wire staples, said staples being positioned substantially crosswise of said meeting edges, said staples being positioned below said nap, each of said staples passing through both of said meeting edges and being clinched against the inner surface of the base portion of said carpet fabric, said tubular covering member having an internal diameter adapted to frictionally and removably engage said stippling roller, the inner surface of said base portion being coated with a layer of rubber cement without penetrating said cord-like nap, said rubber coated inner layer serving to prevent seepage of paint through said base portion, whereby said internal diameter is maintained constant after repeated immersion in paint removing solutions.

CARNIG A. HARPOOTLIAN.
